HUGH CHRISTIE, OF MELROSE, NEW YORK, ASSIGNOR TO THE BIGELOW CARPET COMPANY, OF CLINTON, MASSACHUSETTS.

DESIGN FOR A CARPET.

Specification forming part of Design No. **11,500**, dated November 11, 1879; application filed September 19, 1879.
[Term of patent $3\frac{1}{2}$ years.]

To all whom it may concern:

Be it known that I, HUGH CHRISTIE, of Melrose, New York city, county and State of New York, have invented a new and original Design for a Carpet, of which the following is a specification.

The accompanying photographic illustration represents a face view of my newly-designed carpet.

This invention relates to a new and original design for carpets, oil-cloths, and similar fabrics, and for the border of the same.

It consists of the new ornamentation and grouping of the figures, hereinafter more fully described.

In the photographic illustration, the letter A represents the body of the carpet. B is the border of the same. Upon the body A of the carpet are represented three principal groups, a, b, and c, of peculiar lobated leaves. Each of the leaves in these groups has five lobes, excepting the leaf d in the group c, which has six lobes. Upon the background are furthermore

represented garlands e of flowers, which unite the above-mentioned groups, as shown. The border B contains, in addition to a substantial reproduction of the design shown on the body A, flowers f and branches g.

I claim—

1. The design for a carpet, consisting of the group a of lobated leaves, substantially as shown.
2. The design for a carpet, consisting of the group b, substantially as shown.
3. The design for a carpet, consisting of the group c, substantially as shown.
4. The design for a carpet, consisting of the groups a b c, substantially as shown.
5. The design for a carpet, consisting of the groups a b c, and garlands e, substantially as shown.
